DESIGN FOR A STEAM ELECTRIC IRON

Douglas P. Jones, St. Louis County, and Harry A. Geauque, St. Louis, Mo.

Application May 16, 1938, Serial No. 77,220

Term of patent 14 years

To all whom it may concern:

Be it known that we, Douglas P. Jones and Harry A. Geauque, citizens of the United States, residing in the county of St. Louis and State of Missouri, and the city of St. Louis and State of Missouri, respectively, have invented a new, original, and ornamental Design for Steam Electric Irons, of which the following is a specification, reference being had to the accompanying drawing, forming part thereof.

In the accompanying drawing, Fig. 1 is a plan view of a steam electric iron and Fig. 2 is a side view of a steam electric iron embodying our new design.

We claim:

The ornamental design for a steam electric iron, substantially as shown.

DOUGLAS P. JONES.
HARRY A. GEAUQUE.
